UNITED STATES PATENT OFFICE.

WILLIAM T. WHITAKER, OF GREENVILLE, SOUTH CAROLINA, ASSIGNOR OF SIXTY-SIX AND TWO-THIRDS PER CENT TO FRED M. BURNETT AND THIRTY-THREE AND ONE-THIRD PER CENT TO THOMAS A. BAUGH AND FRED M. BURNETT, ALL OF GREENVILLE, SOUTH CAROLINA.

PICKER-STICK CHECK.

Application filed June 4, 1927. Serial No. 196,527.

My invention relates to picker-stick checks and it is an object of the invention to mount the check so that the picker-stick will bear against the entire width of the strap at the 5 limits of its stroke instead of merely against the upper edge thereof.

Another object of the invention is to provide means for accurately adjusting the length of the stroke of the picker-stick and 10 to provide two methods of attachment of the strap which serves to limit the movement of the picker-stick so that two types of straps may be used all as will be hereinafter more particularly described and claimed.

15 Referring to the accompanying drawings which are made a part hereof and on which similar reference characters indicate similar parts,

Figure 1 is a side elevation illustrating 20 one application of my invention.

Figure 2 is a horizontal section on the line 2—2 of Fig. 1.

Figure 3 is a bottom plan view of a check using a modified form of strap.

25 Figure 4 is a similar top plan view of the structure shown in Fig. 3 with a portion of the strap broken away.

In the drawings reference character 10 indicates a lay and 11 a picker-stick of ordinary construction. A hanger or bracket 12 depends from the lay 10 and to which is secured by means of a bolt 13 a pair of flat plates 14 each of which is provided with a slot 15 of substantially uniform width at one 30 end and being greatly enlarged at its opposite end. The end of the plate adjacent the enlarged end of the slot is rolled over to form a substantially cylindrical pivot 16 about which a short strap 17 may be fastened by means of bolts 18 to the ends of a flexible strap 19 of woven fabric or the like as shown in Figs. 1 and 2.

The plates 14 are secured to the hanger 12 in a manner to permit their being adjusted at the proper angle to permit the strap 19 to bear its full weight against the picker-stick when the same reaches its limit of movement in either direction thereby preventing the strap from stretching a greater 40 amount at the upper edge than at the bottom and becoming unfit for further use. Uniform stretching of the strap may be compensated by loosening the bolt 13 and mov-

ing the plates with or without altering their angular relations as is desired. 65

In lieu of the woven fabric strap 19 which has its ends secured to the slotted plates by means of the strap 17 and bolts 18, a strap of a different construction may be used and in the present instance I have illustrated a strap 20 of leather or other desirable material. The strap 20 is of slightly greater width than the width of the largest portion of the slot in the plates and is reduced at each end adjacent each side to provide a 65 holding knob 21 which serves to maintain the strap in engagement with the flat plates when the knob is inserted through the notch in the plate.

The check straps 19 and 20 are of sufficiently greater length than the distance between the pivots 16 in order to provide sufficient fullness at one side of the plates 14 to form a loop in which the picker-stick 11 is adapted to reciprocate and being adapted to 70 be rested at each end of the strap by the looped end of the strap as shown in Fig. 2.

It will be obvious to those skilled in the art that various changes may be made in my device without departing from the spirit of 75 my invention, and I, therefore, do not limit myself to what is shown in the drawings and described in the specification, but only as set forth in the appended claims.

Having thus fully described my said invention, what I claim as new and desire to 80 secure by Letters Patent, is:

1. A picker-stick check comprising a hanger, a pair of flat, slotted plates secured to said hanger at an angle of 90 degrees to 85 the picker-stick when at the ends of its strokes, said slotted plates being angularly adjustable relative to each other, and a flexible check-strap enclosing said picker-stick and having its ends pivoted to one end of 90 each of said slotted plates, substantially as set forth.

2. A picker-stick check comprising a pair of relatively longitudinally adjustable plates, the free ends of said plates being rolled over 100 to form a substantially cylindrical portion, an aperture formed in each plate adjacent such rolled-over portion, and a flexible check-strap connected to each of said plates adjacent said rolled over portion, substantially 105 as set forth.

3. A picker-stick check comprising a pair of plates provided with longitudinally arranged slots, a fastening bolt extending through said slots for securing the plates in fixed angular longitudinally adjusted position, the extremities of said plates being rolled over to form a substantially cylindrical pivot, and a flexible strap having each end connected to said plates adjacent said pivot, said strap having a portion extending

through said slot and having a knob at its end engaging the edges of the slot to prevent disengagement of the strap, substantially as set forth.

In witness whereof, I have hereunto set ¹⁵ my hand at Greenville, South Carolina this 30th day of May, A. D. nineteen hundred and twenty-seven.

WILLIAM T. WHITAKER.
